TELEPHONE HANDSET BRACKET

Sterling G. Sears, Garden City, N. Y.

Application November 13, 1946, Serial No. 709,567

5 Claims. (Cl. 179—146)

1

This invention relates to brackets for telephone handsets, e. g., devices for supporting and holding a handset at a desired place and in a predetermined position, when not in use.

An extremely common form of telephone handset comprises an elongated handle carrying at one end a telephone instrument, e. g., a receiver or transmitter, and usually having a complementary instrument at the opposite end. The transmitter and receiver, at their respective ends of the handset, are customarily enclosed in more or less bulbous housings, having a cap provided with a central opening or group of openings for passage of sound into or out of the housing. Sometimes in the case of the transmitter but almost always in the case of the receiver, the cap has a dominating margin or peripheral region that lies in a plane. At least in most cases the caps or preferably the housings are turned somewhat toward each other so that the working faces of the instruments, i. e., receiver and transmitter, will be in proper position to be held relatively close to the ear and mouth when the handset is in use.

While the cradle type of handset support commonly found in homes and offices is doubtless sufficient for the ordinary conditions of such use, many telephone installations require a more secure, more compact means for holding a handset when it is not in operation. A few of many examples of such installations are radiotelephone equipment on small boats, railroad locomotives, police cars, aircraft, emergency vehicles, and the like, as well as internal or other wire telephone communication systems in ships, industrial plants, aircraft, and military units; and there are numerous other instances of such requirements. In all cases the telephone handset must be easily and rapidly removable for use, yet at the same time it should be firmly retained, against a wall or panel or other support, when it is not in the hand of the operator. Its retention under such circumstances should be proof against dislodgement by motion of the ship, vehicle or the like in which the equipment is carried, or by the effect of accidental blows from objects or persons required to be in the vicinity of the equipment.

Important objects of the invention are therefore to provide a handset hanger or bracket of improved and simplified construction, suitable for use under conditions such as described above, whereby the handset is securely locked or clamped and yet is easily removed by the operator. Another object is to provide a rugged and

2

durable handset bracket, embodying few parts and yet adapted for use in a wide variety of circumstances and capable of being mounted so as to suspend the handset in any of a variety of positions, e. g., vertically as against a wall or panel, or at an angle, as up and out of the way beneath a shelf or the like. Further objects are to provide an improved device holding the handset by one end alone, with a positively locked yet readily separable grip; to provide a bracket structure readily adjustable in holding tension and likewise readily adjustable to fit various shapes and sizes of handsets; and to provide a novel combination of a handset clamp and co-operating electrical switching means.

To these and other objects, including such as are hereinafter apparent or are incidental to the practice of the invention, certain presently preferred embodiments of the improved handset bracket are shown in the drawings and described hereinbelow by way of example, as illustrating the nature and principles of the invention.

Referring to the drawings:

Fig. 1 is a side elevation of one form of the improved bracket, showing the upper portion of a handset carried thereby, a part of the bracket structure being broken away to show internal features;

Fig. 2 is a perspective view of the device of Fig. 1;

Fig. 3 is another view in the nature of an elevation, as seen from the right of Fig. 1, looking perpendicularly toward the face plate of the bracket;

Fig. 4 is a fragmentary side elevation of one of the arms of the bracket;

Fig. 5 is a side elevation, of another embodiment of the improved bracket, showing the upper portion of a handset mounted therein;

Fig. 6 is an elevational view of the device of Fig. 5, taken in an oblique direction like the view of Fig. 3;

Fig. 7 is an elevation on a reduced scale showing the device of Fig. 1 mounted on a wall with a handset carried therein; and

Fig. 8 is a side view of a switching device such as may be embodied in the bracket.

Referring to Figs. 1 to 4 inclusive, the illustrated bracket includes a seat comprising a plate 10 disposed in a generally vertical position, although conveniently at somewhat of an angle to the vertical, as shown, where the bracket is to be mounted against a wall with a handset of the most usual type carried in vertical position.

55 The lower end of the plate 10 is bent outwardly

and slightly upward to form a shelf 11, to which is secured, by riveting, welding or other effectively firm attachment, the central flat portion 12 of a gripping member provided with spaced arms 13, 14. The member comprising the portion 12 and arms 13, 14 is conveniently cut or otherwise fashioned from heavy stock of stiffly resilient sheet metal—e. g., both the member last described and the plate 10 with its extension 11 may be made of steel or stiff brass in thickness $\frac{1}{8}$ to $\frac{1}{4}$ inch—and the arms 13, 14 are so shaped and bent as to curve both outwardly and upwardly from the lower end of the plate 10. The inner face of the end of each arm is provided with a gripping portion 15 which may comprise a button-like member having a curved surface as shown (see also Fig. 4) and preferably made of hard fibre or other non-abrasive but relatively hard material. The shape of the arms 13, 14 in cooperation with the face plate 10 is such that the bulbous housing of an instrument, e. g., the receiver, at the end of the handset handle may be embraced by these parts.

As will be seen from Figs. 1 and 7, the illustrated example of a handset comprises a handle portion 16 terminating at one end in a portion of the hemispherical surface 17 of the receiver housing, which is closed by the usual cap 18. The other end of the handle 16 terminates in the housing for the other instrument of this type of handset, i. e., the transmitter, such housing being similarly hemispherical as at 19 and having a cap 20. It will be appreciated that the housing structure for the instruments of the handset may vary somewhat in size or configuration, and it is manifestly immaterial to the operation of the bracket whether the lower end of the handle 16 carries any particular form of instrument or housing. Whereas the housing 17 has been described as hemispherical, it will be understood that such term is used in a generic rather than a strict geometric sense, i. e., to include other curved surfaces, whether ovoid, paraboloid or the like, having a generally ball-shaped curve. Ordinarily the cap 18 includes a marginal region 22 lying in a plane with which the face 10 of the bracket may abut, although it will be appreciated that the bracket device may be readily adapted for cooperation with instruments having other shapes of faces or caps than the simple and regular arrangement here shown.

Referring particularly to Fig. 1, the arms 13, 14 have a normal position such that as the handset is inserted by sliding the cap of the receiver housing down along the plate 10 the gripping elements 15 of the arms engage the curved surface of the housing conveniently at or before the latter reaches a position indicated by the dot-and-dash lines 24. In such position the high region or regions of the hemispherical surface relative to the plate 10 are disposed above the ends of the arms. Consequently as the receiver housing is moved down, the arms are forced outwardly by its curved surface, passing over the high points of curvature and then moving back toward the plate as the receiver housing comes to rest at the end of its travel; i. e., against the upper surface of the transverse portion 12. In approaching and reaching the high spots of the receiver surface the arms are in effect cammed outwardly; that is to say, each arm is moved as if it were a spring pressed follower sliding (with some friction) over a rising cam surface provided by the receiver.

With the handset in its final position of rest,

the ball-shaped elements 15 of the arms now engage localities of the hemispherical housing surface that are beyond the highest regions of the latter relative to the plate 10, but are still somewhat sprung or distorted from their normal position. In this relationship the ends of the arms, specifically the gripping members 15, engage the housing surface and exert spring pressure on it in a substantially normal direction so that the receiver is firmly clamped between the arms and the cooperating plate 10. The handset can be removed simply by forcibly sliding it in an upward direction, along the plate 10, but in so doing the arms must again be cammed outwardly, so to speak, against their strong spring pressure, in order to release the high or peak regions of the curved surface.

These relationships are further represented by the dot-and-dash line 25, corresponding to a central plane through the receiver housing and perpendicular to the drawing when the housing is in the dot-and-dash line position 24, and a corresponding dotted line 26 representing the same plane when the receiver is in its fully seated, full-line position. Since these lines correspond to the high regions or spots of the receiver housing, relative to the seat 10, it will be clearly apparent that the ends of the arms 13, 14, and specifically their gripping elements 15, must pass over and come to rest beyond the high regions, in order to seat the receiver. In addition the lateral spacing of the arms, whereby their ends rest on surface regions that are lower also than the curved area between them, contributes to the positive lock against horizontal as well as vertical displacement of the handset.

To mount the bracket, as on a wall or panel, a box-like supporting structure 28 may be provided, secured to the rear side of the plate 10 and having a rear face comprising mounting tabs 30 (of which one is shown in Fig. 2, it being understood that a similar tab is provided on the other side of the box 28), which can be disposed at an appropriate angle to the face plate 10. For example, a handset of the type shown in the drawings commonly has the face of its receiver disposed obliquely to the handle 16, so that if it is desired to suspend the handset with the handle in a vertical position, and thus as close to the wall or panel as possible, the secured position of the receiver housing should be one in which the face of the latter makes a corresponding oblique angle with the wall, as shown in Fig. 7.

A supplemental feature of the improved bracket construction, which the latter is peculiarly adapted to include, comprises a switch generally indicated by its housing 32, that may be mounted for instance on the underside of the plate 10 and within the box 28. This switch may be of the push button type, having an operating member or button 34 projecting through an opening in the plate 10, at such position that when the receiver is moved down into secured relation, the member 34 is cammed, i. e., moved inwardly by the face of the receiver, for example by the marginal portion 22 of its cap. It will be appreciated that any of a considerable variety of switching devices, having one or more poles and including contacts to be opened or closed by inward displacement of the member 34, may be employed in the described combination. Simply for purposes of illustration, Fig. 8 shows a switch having a fixed contact 35 facing rearwardly from the panel, and a cooperating contact 36 mounted on a light spring 37 biasing it into engagement

with the contact 35. The operating member 34 is disposed so that its inner end engages the spring 31 and separates the contacts when the member is moved inwardly by the handset receiver. On removing the receiver, the spring 31 pushes the member 34 outwardly and at the same time engages the contacts 36, 35 so that a circuit may be closed, for instance, in the line connecting the handset to the communication equipment with which it is used.

The modification shown in Figs. 5 and 6 includes a corresponding seat having a flat plate portion 40 and also a projecting fulcrum portion or ear 41 at the upper end of the plate portion 40. This fulcrum or bearing portion 41 extends upwardly from the plate and may have a further portion 42 flanged upwardly, to facilitate insertion of the receiver housing beneath the projection 41, in the manner more fully explained below.

The lower end of the seat also has a projection 43 to which is secured the transverse portion 44 of a member fashioned to provide a pair of spring arms 45, 46 which curve outwardly and upwardly in a manner generally similar to the arms 13, 14 of Figs. 1 and 2. The ends of the arms 45, 46 may on their inner sides have ball-shaped friction or gripping elements (not shown) identical with the members 15 of Figs. 2 and 4, for the same purpose.

In the arrangement of Figs. 5 and 6 the handset is inserted by placing the upper edge of the receiver cap beneath the projection 41 of the seat, or approximately at the intersection of such projecting portion and the face portion 40, and rocking the handset downwardly about the seated edge of the cap until the receiver face abuts the plate 40. Although for many purposes a simple metallic member will suffice for the seat, it is preferred to surface the portions 40, 41 and 42 with a somewhat resilient material to avoid even minor shocks on the plastic receiver housing and cap, such as might chip or otherwise damage the handset, when the device is inserted in the manner described. Accordingly a thin sheet 47 of rubber or the like is provided as a facing along the outer surface of the member 40, 41, 42.

The arrangement of Fig. 5 embodies the same positive locking feature as is characteristic of the device shown in Fig. 1. Thus when the handset is first brought to the bracket for insertion, the receiver housing 48 may occupy, for instance, the position shown in dot-and-dash lines 49, where the ends of the arms have begun to engage the curved surface of the housing. As the handset is then rocked downwardly, i. e., by pulling the handle 50 down around the projecting portion 41 as a fulcrum—the upper edge 51 of the receiver cap having been inserted thereunder—the arms 45 are cammed and sprung outwardly by the curved surface of the housing. The high regions of the housing surface relative to the seat, specifically the projecting portion 41 of the seat, pass under the ends of the arms, and as the receiver reaches the full-line position with its face abutting the plate 40, the ends of the arms have moved beyond the high regions, and come to rest against somewhat lower localities of the curved surface relative to the ear 41 or its intersection with the plate 40. In the device shown, although not necessarily in all embodiments, the upper edge of the receiver cap has somewhat of a rolling motion of its surface relative to the seat portions 41 and 40 during insertion and removal, which facilitates those operations.

The dot-and-dash line 52 represents a medial plane of the receiver housing in its dot-and-dash line position 49, and the dotted line 53 represents such a plane in its full-line position, in similar fashion to corresponding lines in Fig. 1. From these lines, which indicate the high localities of the receiver housing, i. e., the uppermost part of their curved surfaces relative to the pressure region of the bracket seat, it will be seen clearly that the ends of the spring arms 45, 46 must be cammed outwardly either upon inserting or removing the receiver, and that in the full-line, secured position, the arms exert spring pressure in a direction substantially normal to the curved surface, to clamp the receiver in place.

The bracket structure shown in Figs. 5 and 6 may be mounted in any desired fashion, for example as with a box support of the type shown in Fig. 1, or with an even simpler form of flanged support represented at 53 in the drawing. If desired, the arrangement may be similarly provided with a switch 54 to be actuated by the face of the receiver when it is inserted in the bracket, the switch having an operating member 55 normally projecting through the plate 40 and having a curved end (like the member 34 of Fig. 2) that is pushed inwardly, by the receiver cap, to change the relation of contacts in the switch. Whereas the device of Fig. 1 may permit slightly more rapid insertion or removal of a handset, the form of Fig. 5 is at present preferred for instruments of heavier type, and particularly for a relatively deep receiver housing having a more truly spherical curvature than the somewhat paraboloid shape used in certain handsets. The structure of Fig. 5, in which the ear 41 provides an additional guard against upward displacement of the receiver, is also preferable where there may be extraordinarily severe shocks tending to dislodge the handset, e. g., as in vehicles to be operated over rough ground, or as in aircraft, which may suffer such shocks in landing.

Figs. 3 and 6, respectively, show rear views of the handset, i. e., the receiver portion thereof, as retained in the the corresponding form of the improved bracket. In each case the arms are in engagement with the rear curved surface of the receiver or other instrument housing and the handle of the handset extends down between the arms.

The device is very simple and yet positive in action; in either embodiment shown, the handset is inserted merely by pulling down on its handle, and by this convenient, single movement, the holding parts are brought into a locking position. That is to say, the spring arms 13, 14 then hold the handset not merely by frictional engagement, but by actually clamping the receiver housing against the seat and from a direction such that it can not be displaced by any accidental slippage between the housing surface and the spring arms. The inner surfaces of the ends of the latter, it will be noted, preferably face and exert maximum spring pressure toward a vertically and horizontally central region of the seat—thus in Fig. 5 toward or below the intersection of the flat and camming portions. Only by forcing the handset in a direction reverse to that of its insertion, so as to cam the arms outwardly against their stiff spring pressure, can the receiver be removed; it is, in effect, snapped into and out of retained position.

This relationship, as distinguished from a simple rest or hook for the handset, is particularly important in mobile installations where vibra-

tion, pitching, rocking, or other motion would tend to dislodge the instrument. The structure can be made to fit any of a wide variety of handsets, even where the bulbous receiver housing is shallow or flattened as in one prior type of instrument or has the more complex shape of an older type of device commonly used in general telephone service; in fact, any given bracket can be readily accommodated to a considerable variation of shape, or of receiver size and of holding pressure thereon, by bending the spring arms toward or away from the seat. While the drawings show the instrument held vertically, as if simply suspended, the bracket may be mounted in a variety of angles, even such that the handset would be retained in a horizontal direction, as under a shelf or beneath the dash board of an automobile.

The bifurcated arrangement of the spring gripping means, i. e., spacing of the arms 13, 14 or 45, 46, permits the handle of the handset to pass readily between them, and yet cooperates in preventing dislodgement of the instrument as by accidental blows upon the handle. Thus in the devices shown the handset can swing only about an axis centrally perpendicular to the receiver face; but even such swing is positively limited by the arms, which are quite rigid in an edge-wise direction. Moreover, the handset can not be dislodged by striking or pushing its lower part toward the surface upon which the bracket is mounted; in fact it can only be removed by intentional use of the relatively considerable force needed to snap the high regions of the receiver housing past the spring arms.

Although the snap operation is a preferred feature of the invention, in some circumstances structures of the sort shown can be designed or adjusted for use without it, for example so that as the handset is inserted each arm only rides to and upon but not beyond a high part of the receiver housing. The latter is then pressed against the seat by simple spring action of the arms, the holding effect being satisfactory for many office or home installations, and being aided, if desired, by making the high spots of the housing in the form of flattened regions of appreciable area in the paths of the arms. In such cases there should of course be ample spring pressure and friction, to insure a satisfactory grip.

The elements of the bracket are extremely simple, being readily manufactured of sheet material, and the device is relatively light but rugged, so that even considerable abuse will not bend the arms or otherwise damage the intended relationship of the parts. While in some cases the seat and arms may be fashioned of a single piece of metal, particularly if it is carefully treated to provide resilience and rigidity in the proper places, easier manufacturing control of such characteristics is usually obtained with a two-piece construction as shown. Likewise while in certain cases the spring arm effect may be achieved by supplementary spring structure for rigid arms or members or on the seat or by making a portion of the seat, e. g., its lower end, resilient, the embodiment of inherent resilience in the arms as described is of notable advantage, especially for reliability in use or economy in manufacture. In preferred forms of the bracket the switch arrangement cooperates effectively with the other elements, e. g., in its simple mounting relationship to the face plate and in the peculiar adaptability of the manner of inser-

tion and removal of the receiver, to operation of the switch. As stated, the device may be mounted at any desired angle, reference hereinabove and in the appended claims to vertical arrangements and to upper and lower parts or the like, being simply intended for convenience in characterizing mutual relationships as if by reference to such disposition (e. g., as in the drawings), rather than as a requirement of use in an upright position. It will also now be apparent that the bracket is of substantial utility for holding telephone devices, herein considered handsets, that may embody only one instrument, e. g., a receiver or transmitter, rather than two.

It is to be understood that the invention is not limited to the specific structures herein shown or described but may be embodied in other forms without departure from its spirit.

I claim:

- 20 1. A bracket for removably holding a telephone handset which has a bulbous instrument housing from which a handle extends, comprising spring means adapted to grip the housing under spring pressure, including a seat and cooperating gripping means disposed to engage said housing upon inserting the latter between said seat and gripping means, said gripping means having a plurality of gripping portions substantially spaced from each other and each spaced from the seat by a distance slightly less than the thickness of the inserted housing and said gripping means being thereby adapted to be moved outward relative to the seat, against the spring pressure, by the surface of the housing as the latter is inserted beneath the gripping portions, whereby the gripping portions engage said surface at a corresponding plurality of localities under said spring pressure, to hold the inserted housing against the seat.
- 25 2. A bracket for removably holding a telephone handset which has a handle and an instrument housing having an operating face and a bulbous rear surface joined by the handle, comprising a flat seat and cooperating spring arms extending from the lower end of said seat, said seat and arms being disposed to engage the instrument housing between them upon insertion of said housing by moving its operating face down along said seat, said arms being spaced for the handle to pass between and extend below them upon said insertion of the housing, and said arms being each spaced from the seat by a distance slightly less than the thickness of the inserted housing and being thereby adapted to pass over a high region of said bulbous surface as the housing is inserted, and to engage said surface under spring pressure at localities on the further side of said high region.
- 30 3. A bracket for removably holding a telephone handset which has a handle and a receiver housing having an operating face and a hemispherical rear surface joined by an end of the handle, comprising a seat having a flat portion and a bearing portion extending out from the upper end of said flat portion, and cooperating spring arms extending from the lower end of said flat portion, said seat and arms being disposed to engage the receiver housing between them upon insertion of said housing by placing an edge of its operating face beneath the bearing portion of the seat and rocking the housing into abutment of its said face against said flat seat portion, said arms being spaced apart for the handle to pass between and extend below them upon said insertion of the housing, and being each

spaced from the seat by a distance slightly less than the thickness of the inserted housing, and said arms by their disposition being adapted to pass over a high region of said hemispherical surface as the housing is rocked into engaged position, and to engage said surface under spring pressure at localities on the further side of said high region.

4. A bracket for removably holding a telephone handset which has a handle and an instrument housing having an operating face and a curved rear surface joined by the handle, comprising spring means adapted to grip the housing under spring pressure, including a seat and cooperating arms extending outwardly from, and into facing relation with said seat, said seat and arms being disposed to engage the instrument housing with its operating face against the seat upon insertion of said housing between the seat and arms, said arms being spaced for the handle to pass between them upon insertion of the housing, and being each spaced from the seat by a distance slightly less than the thickness of the inserted housing, and said arms by their disposition being adapted to pass over a high region of said curved surface as the housing is inserted, and to engage said surface under spring pressure at localities on the further side of said high region, for clamping the handset in place.

5. A bracket for removably holding a telephone handset which has a bulbous instrument housing from which a handle extends, comprising spring means adapted to grip the housing under spring

pressure, including a seat having a flat portion and a projecting portion extending out from one end of said flat portion and cooperating arms extending outwardly from the seat and into facing relation therewith, said arms and said flat and projecting portions of the seat being mutually disposed to embrace the instrument housing upon insertion of same in abutment with inner faces of said portions and arms, and said arms being spaced from the seat, at their ends, by distances slightly less than the thickness of the embraced housing and being thereby adapted at said ends to engage the surface of the housing under said spring pressure, to hold the inserted housing against the seat.
